US0D1068816S

(12) **United States Design Patent** (10) **Patent No.:** **US D1,068,816 S**
Harvey et al. (45) **Date of Patent:** **** Apr. 1, 2025**

(54) **DISPLAY SCREEN OR PORTION THEREOF WITH A GRAPHICAL USER INTERFACE**

(71) Applicant: **PassiveLogic, Inc.**, Salt Lake City, UT (US)

(72) Inventors: **Troy Aaron Harvey**, Brighton, UT (US); **Yen-Hsiu Liu**, Yilan (TW)

(73) Assignee: **PassiveLogic, Inc.**, Holladay, UT (US)

(**) Term: **15 Years**

(21) Appl. No.: **29/929,239**

(22) Filed: **Feb. 20, 2024**

Related U.S. Application Data

(63) Continuation of application No. 29/817,801, filed on Dec. 3, 2021, now Pat. No. Des. 1,023,028.

(57) **CLAIM**

The ornamental design for a display screen or portion thereof with a graphical user interface, substantially as shown and described.

DESCRIPTION

The FIGURE is a front view of a display screen or portion thereof with a graphical user interface.

The outermost broken lines shown in the FIGURE illustrate a display screen or portion thereof and form no part of the claimed design. The other broken lines in the FIGURE show portions of the graphical user interface that form no part of the claimed design.
